HEATING APPARATUS

Bernard Geerg, Scarsdale, N. Y., assignor, by
mesne assignments, to American Radiator &
Standard Sanitary Corporation, New York,
N. Y., a corporation of Delaware

Application April 20, 1938, Serial No. 203,033

9 Claims. (Cl. 122—250)

This invention relates to heating apparatus and more particularly to boiler furnaces of the type which are used for heating buildings such, for example, as dwelling houses, stores, etc.

5 An object of my invention is to produce a boiler furnace which is highly compact and is very low in weight for its capacity, and one which is capable of being brought from an off-period in its operation to its normal operating capacity within a 10 relatively short period of time.

A further object is to provide a boiler furnace of the above character which is efficient in operation and one whose manufacturing and installation cost compares favorably with prior boilers 15 of the same capacity.

The invention consists in the novel construction and combination of parts, to be more fully described hereinafter, and the novelty of which will be particularly pointed out and distinctly 20 claimed.

In the accompanying drawings, to be taken as a part of this specification, I have fully and clearly illustrated a preferred embodiment of my invention, in which drawings—

25 Fig. 1 is a vertical sectional view through a boiler furnace constructed in accordance with the present invention, the view being taken on the line 1—1 of Fig. 3;

Fig. 2 is a horizontal transverse sectional view 30 taken on the line 2—2 of Fig. 1; and

Fig. 3 is a horizontal transverse sectional view taken on the line 3—3 of Fig. 1.

Referring now in detail to the construction illustrated, the reference numeral 10 indicates a 35 boiler furnace which comprises, in general, an outer enclosing jacket 11 of sheet-metal, a firing chamber 12, a combustion chamber 13, a steam and water drum 14 and gas passages 15 and 16 surrounding, respectively, the combustion chamber 13 and drum 14 and connecting the gas-exit of the chamber 13 with a flue gas outlet 17, the latter extending through the upper part of the outer jacket 11. The main or general elements of the furnace, just referred to, are all symmetrically arranged about a vertical axis extending through the center of the furnace.

The firing chamber 12 is preferably located in the lower central part of the furnace and, in so far as certain of the broader aspects of my invention are concerned, may be of any suitable construction. In the form shown, the chamber 12 is advantageously of a unitary construction and comprises an inner lining member 20 of heat-resistant steel forming the bottom and side walls 50 of the firing chamber, and having an opening 21

in one side wall through which a fluid fuel burner 22 of any suitable type may discharge fuel mixed with air. The burner shown is an oil burner of the gun type. To the exterior of the lining member 20 is applied a suitable heat insulating material indicated at 23. The chamber 12 is open at the top as shown, and registers with an opening 25 formed in the center of a supporting base plate 26 arranged horizontally across the interior of the furnace. The upper edge of the lining member 20 is provided with an integral flange 27 through which bolts 28 extend and thereby serve as a means for securing the upper edge of the firing chamber to the base plate 26 and about the opening 25. As the lining member 20 is 10 formed of heat-resistant steel and is surrounded with the insulating material 23, a relatively high temperature may be maintained in the chamber, which, as is well known, is conducive to positive ignition and efficient combustion of the fuel entering from the burner 22.

The base supporting plate 26 is suitably formed of heat-resistant steel and is supported in the position shown by a plurality of posts 29 extending downwardly therefrom and resting at 25 their lower ends on the basement foundation. The extreme lower part of the furnace 10 is closed by a horizontally extending sheet-metal base member 30. The base member 30 is secured to the lower part of the posts 29 and aids in supporting the firing chamber 12.

The combustion chamber 13 is here shown as being arranged centrally over the opening 25 and as being cylindrical in shape and extending upwardly from the base supporting plate 26. The lower end of the combustion chamber communicates with the firing chamber 12 through the opening 25. In so far as certain of the broader aspects of my invention are concerned, the wall structure defining the vertical cylindrical combustion chamber may be of any suitable type. In the preferred embodiment shown the chamber 13 is defined by an upright cylindrical wall structure 35 having hollow water spaces communicatively connected to the steam and water drum 14.

The cylindrical wall structure 35 of the combustion chamber is formed by a plurality of superposed helically wound pipe coils 36. The coils 36 may be made of a metal having a relatively high coefficient of thermal conductivity, such for example, as copper. Six coils 36 are shown, arranged one above the other, and each of the coils is provided with an inlet end 37, which extends tangentially from the cylindrical 50 55

formation of the wall structure 35 and is connected at its outer end to a vertically arranged downtime header 39 in the passage 15, and each coil 36 is also provided with an outlet end 40 which also extends tangentially from the cylindrical portions of the wall structure 35 and is connected to a vertically arranged uptake header 41 adjacent the header 39 in the passage 15. As shown in Figs. 1 and 3, each coil is helically wound around the vertical axis of the furnace for almost 720°; that is to say, beginning at the inlet end 37 of a given coil 36, the coil extends completely around the furnace once, and then around the furnace again until it joins with the cutlet header 41. Adjacent convolutions of a given coil and adjacent convolutions of adjacent coils are arranged one above the other to provide the cylindrical wall structure 35. Each of the coils is so wound and so connected into the headers 39 and 41 that it continually slopes upward from where it joins the downtime header to the point where it joins the uptake header, thereby assuring the effective circulation of water in the boiler and the passage of steam bubbles, as they are formed, through the coil, the uptake header 41 and to the drum 14.

The upper ends of the uptake and downtime headers 39 and 41 are connected into the lower part of the drum 14. The upper end of the downtime header is flush with the inside bottom surface of the drum, but the upper end of the uptake or steam header extends partly into the drum in order to assume circulation of water in the right direction at starting. The lower end of the uptake header is closed as shown, and the lower end of the downtime header is connected to the condensate return pipe 43 of the steam heating system in the building where the furnace 10 is installed.

The combustion chamber 13 is provided with a gas-exit opening 45 in its side and at points adjacent the headers 39 and 41, and the gas-exit opening 45 extends for the full height of the combustion chamber as can be seen from an examination of Fig. 1. Laterally, the opening 45 extends from the point where the inlet ends 37 of the several coils 36 leave the cylindrical formation of the wall structure 35 to the point where the outlet ends 40 leave the cylindrical formation. The wall structure 35 is closed and continuous except at the opening 45. The spaces between adjacent convolutions of the coils are closed by a plurality of steel bands 47 which extend from one side edge of the opening 45 and about the combustion chamber to the other side edge of the opening 45. The opening 45 is thus provided by the unclosed spaces between adjacent convolutions, and by relatively large spaces 48 between convolutions resulting from the fact that the inlet and outlet ends 37 and 40 extend tangentially away from the cylindrical formation of the wall structure 35.

The steam and water drum 14 is arranged above and closes the top of the combustion chamber. While the drum 14 may be constructed in any suitable manner in so far as the broader aspects of my invention are concerned, I prefer that the drum be made of sheet-metal walls welded together to form an integral structure capable of withstanding the internal pressures reached in boilers of the type disclosed. The drum 14 comprises a horizontal bottom wall 50 closing the top of the chamber 13, upright side walls 51, and a top wall 52. The bottom wall 50 is provided with an outwardly extending flange 53 and a de-

pending flange 54, for purposes which will presently appear. The drum 14 is formed with a laterally extending portion 55 to which the upper ends of the headers 39 and 41 are connected. The top wall 52 is formed with a steam outlet opening 56 in the central portion thereof to which is connected the steam supply pipe 57 for the steam heating system of the building in which the furnace is installed.

The combustion chamber 13 and steam and water drum 14 are advantageously supported from the base plate 26. As shown, a plurality of vertical supporting posts 60 are arranged in the passage 15 and about the wall structure 35 of the combustion chamber 13, and these posts are suitably secured at their lower ends by bolts 61 to the upper face of the base plate 26. The posts extend upwardly to the drum 14 and are secured at their upper ends to the flange 53 by bolts 62. The side wall structure 35 of the combustion chamber is secured to the posts by means of a plurality of bolts 64 and spacers 65 encircling the bolts. The bolts 64 extend through aligned openings in the posts 60 and in the steel bands 47 and the spacers 65 are arranged between the posts and bands. Thus, the bolts 64 and spacers 65 serve as a means for clamping the closure bands in their proper position between adjacent convolutions of the coils 36, as well as a means for securing the wall structure 35 in supporting relation with respect to the posts 60.

At the lower end of the combustion chamber 13, the coils are properly positioned with respect to the opening 25 by an upstanding flange 10 formed integral with the base plate 26 and extending symmetrically about the vertical axis of the furnace 10 just inside of the coils. The flange 10 does not extend entirely about the vertical axis of the furnace; but terminates at the sides of the opening 45 so as not to interfere with the outflow of gases from the chamber 13. Likewise, the flange 54 depending from the flange 53 of the bottom wall 50 of the steam and water drum 14, extends about the vertical axis of the furnace except at the opening 45 and serves to position properly the uppermost coil 36 of the combustion chamber 13 with respect to the drum 14 and the headers 39 and 41.

Spaced outwardly from the side wall structure 35 of the combustion chamber 13, and from the side walls 51 of the steam and water drum 14 is a wall member 75 which extends symmetrically about the vertical axis of the furnace 10 and defines with the outer surface of the wall structure 35 and the wall 51 of the drum 14, the passages 15 and 16. The passages 15 and 16 are open at each end. The passage 15 communicates at one end with the gas-exit opening 45 of the combustion chamber and extends almost entirely around the outside of the combustion chamber, as shown in Fig. 3. The bottom of the passage 15 is defined by peripheral portions of the base plate 26 and the top of the passage 15 is defined by plates 76 extending horizontally and between the flange 53 of the wall 50 and the wall 75. Angle brackets 77 support the edges of the plates 76 at the wall 75. A vertical partition plate 78 extending from the wall 75 to the outer surface of the wall structure 35 and suitably secured to the latter serves as a means for separating the ends of the passage 15.

The passage 16 is connected at one end through an opening 79, provided by the arrangement of the horizontal partition plates 76, to the end of 75

the passage 15 which is remote from the gas-exit opening 45. The passage 16 overlies the passage 15 and extends about the walls 51 of the steam and water drum 14 approximately 315° (see Fig. 2); the ends of the passage being separated by the extension 55 of the drum 14, to which the upper ends of the uptake and downtake headers 39 and 41 are respectively connected. The top of the passage 16 is closed by a top wall member 82 extending horizontally across the interior of the furnace and supported at its periphery by the wall member 75.

In so far as the broader aspects of my invention are concerned, the side wall member 75 and the partition plates 76 may be formed of any suitable material. However, in the preferred embodiment shown, these wall members are formed of heat-resistant steel. The side wall member 75 and the top wall member 82 are spaced inwardly from the enclosing jacket 11 and the spaces between the outer surfaces of these wall members and the enclosing jacket are preferably filled with a heat insulating material indicated at 84. The material 84 may be of any of the well known types on the market capable of effectively retaining the heat within the furnace. The top wall member 82 and the top wall of the jacket 11 with the insulating material 84 therebetween may be constructed as a removable cover unit so as to facilitate inspection and cleaning. The plates 76 may also be removed for cleaning after the cover unit is removed.

From the above, it is apparent that I have provided a boiler of the flash type which is highly compact and efficient. The ratio of weight to capacity in the boiler disclosed is extremely low when compared with conventional types of boilers, and the time required to reach a normal operating capacity from an off-period is very low. This time is much less when the boiler is also used to heat hot tap water because in such a case, the temperature of the boiler water is usually maintained around 150° to 180° F. during off-periods. On account of the relatively large water capacity of the drum 14, the boiler is well adapted for the installation of a hot tap water heating coil. A coil 87 of the hair pin type may be readily placed in the drum 14 and connected to the conventional hot water storage tank (not shown).

Due to the particular construction and arrangement of the combustion chamber 13, drum 14, gas passages 15 and 16, and the wall member 75, the hot gases of combustion contact an unusually large area of water filled heat absorbing wall surfaces. The combustion gases, after contacting the inner surfaces of the coils 36 and the bottom wall 50 of the drum 14, flow out of the combustion chamber and contact the headers 39 and 41 in the passage 15. The gases then pass completely around the combustion chamber and contact the outer sides of the tubes 36. The gases then flow upwardly into the passage 16 where they pass almost entirely around the drum 14 and contact the side walls 51 thereof before reaching the outlet 17. This construction and arrangement results in the maximum amount of heat in the gases being given up to the water in the boiler and a low stack temperature of the combustion gases. Furthermore, due to the novel construction and arrangement of the relatively small metal tubes 36, a high rate of heat transfer is had between the combustion gases and the water in the boiler. As the wall structure of the combustion chamber is formed by pipe coils, the

amount of water subjected to the fire is relatively low, yet the water is spread over a large area. Consequently, the boiler can be quickly brought to normal steaming within a relatively short period of time. However, even though the tube structure contains a relatively small amount of water, the boiler is decidedly safe to operate on account of the relatively large water space in the drum 14.

A further feature which makes possible quick steaming and efficient heat transfer is the steel wall member 75. As the latter is backed by the heat insulating material 84, relatively little heat is lost to the surrounding atmosphere. Therefore, heat absorbed from the gases flowing through the passages 15 and 16 is radiated back to the water in the boiler. This flow of heat from the wall 75 by radiation may be increased by providing an inner dark surface.

Thorough circulation of water between the tubes and drum 14 is had because I have provided a plurality of tubes and because the ends of each of the tubes are connected directly to the headers 39 and 41. As the tubes slope upward there is no problem of water circulation and of transmission of the steam bubbles as soon as they are formed to the relatively large capacity drum 14. This latter makes the boiler safe to operate and gives a steady and even supply of steam to the pipe 57.

It is to be noted that while I have shown and described a boiler furnace which operates efficiently to generate steam for heating building spaces, the present invention in all of its aspects is not to be considered as being so limited, because the structure disclosed is also well adapted for use as a hot water boiler, in a manner which will be apparent to those skilled in the art.

What I claim and desire to secure by Letters Patent of the United States is as follows:

1. In a boiler, the combination of means defining an upright combustion chamber having a gas-exit opening in one side and comprising a plurality of superposed spaced pipe coils arranged substantially symmetrical about a vertical axis, and means for closing the spaces between coils to provide with the coils a continuous wall surface except at the gas-exit opening; wall means defining a steam and water space above said coils; and water circulating means communicating connecting said coils and said space.

2. In a boiler, the combination of means defining an upright combustion chamber having a gas-exit opening in one side and comprising a plurality of superposed spaced pipe coils arranged substantially symmetrical about a vertical axis, and means for closing the spaces between coils to provide with the coils a continuous wall surface except at the gas-exit opening; wall means defining a steam and water space above said coils, and uptake and downtake headers depending from said steam and water space and connected, respectively, to the opposite ends of said pipe coils.

3. In a boiler, the combination of means defining an upright combustion chamber having a gas-exit opening in one side and comprising a plurality of helically wound pipe coils arranged one above the other and about a substantially vertical axis with adjacent convolutions spaced slightly from one another, and means for closing the spaces between adjacent convolutions to provide a continuous wall surface except at the gas-exit opening; wall means defining a steam and water space above said coils; and water circulat-

ing means communicatively connecting said coils and said steam and water space.

4. In a boiler, the combination of means defining an upright combustion chamber having a gas-exit opening in one side and comprising a plurality of superposed spaced pipe coils arranged one above the other and substantially symmetrical about a vertical axis, and means for closing the spaces between coils to provide a continuous wall surface except at the gas-exit opening; wall means defining a steam and water space above said coils; water circulating means communicatively connecting said space and said coils; wall means spaced outwardly from said coils to provide therewith a gas passage surrounding at least partially said coils and connected at one end to said gas-exit opening and having an outlet end circumferentially spaced from said gas-exit opening; said last-named wall means having a gas outlet opening connected to the outlet end of said passage.

5. In a boiler, the combination of means defining an upright combustion chamber having a gas-exit opening in one side and comprising a plurality of helically wound pipe coils arranged one above the other and about a substantially vertical axis with adjacent convolutions spaced slightly from one another, and means for closing the spaces between adjacent convolutions to provide a continuous wall surface except at the gas-exit opening; wall means defining a steam and water drum closing the top of said combustion chamber; wall means spaced outwardly from said coils to define an open-ended gas passage connected at one end to said gas-exit opening; uptake and down-take headers arranged in said gas passage adjacent said gas-exit opening and connected at their upper ends to said drum; means for connecting the uptake header to the upper ends of said coils and the downtake header to the lower ends of said coils.

6. In a boiler, the combination of means defining a combustion chamber having a gas-exit opening in one side and comprising a plurality of superposed helically wound pipe coils arranged with the convolutions of the coils in overlying relation and forming a substantially vertical cylinder; each of said coils having lower and upper end portions extending outwardly therefrom at points adjacent said opening; downtake and uptake headers arranged in adjacent relation outside of said combustion chamber at said gas-exit opening and connected, respectively, to said lower and upper ends; means for closing the spaces between adjacent convolutions except between the points where the upper and lower ends leave the cylindrical formation so that the spaces between convolutions left by the outwardly extending ends form the gas-exit opening; and wall means defining a steam and water space communicatively connected to said uptake and downtake headers.

7. A boiler comprising an inner wall structure defining an upright cylindrical combustion chamber closed across its top, having a firing opening in its bottom, and having a gas-exit opening in an upright side thereof, and the inside surfaces of said combustion chamber being formed contin-

uous except for said firing opening and said gas-exit opening so as to provide for the out flow of combustion gases only through said gas-exit opening; said wall structure being formed with hollow interior water spaces surrounding the sides of said chamber and with a hollow interior water and steam space over the top of said chamber; an outer cylindrical wall structure enclosing said inner wall structure and spaced from the latter to define therebetween an annular space; wall means arranged across and closing said space vertically at one side of said gas-exit opening to provide in said space an annular passage for flue gases having an inlet end communicating with said gas-exit opening and an outlet end circumferentially spaced from said inlet end.

8. A boiler comprising an inner wall structure defining an upright cylindrical combustion chamber closed across its top, having a firing opening in its bottom, and having a gas-exit opening in an upright side thereof, and the inside surfaces of said combustion chamber being formed continuous except for said firing opening and said gas-exit opening so as to provide for the out flow of combustion gases only through said gas-exit opening; said wall structure being formed with hollow interior water spaces surrounding the sides of said chamber and with a hollow interior water and steam space over the top of said chamber; an outer cylindrical wall structure enclosing said inner wall structure and spaced from the latter to define therebetween an annular space; a first partition wall means arranged across said space above said gas-exit opening to divide said space horizontally into lower and upper gas spaces; a second partition wall means arranged across said lower gas space at one side of said gas-exit opening to provide in said lower gas space a first annular gas passage having an inlet end communicating with said gas-exit opening and an outlet end circumferentially spaced from its inlet end and communicating with said upper gas space; a third partition wall means arranged across said upper gas space at one side of the outlet end of said first annular passage to provide in said upper gas space a second annular gas passage having an inlet end communicating with the outlet end of said first annular gas passage and having an outlet end circumferentially spaced from its inlet end.

9. A boiler comprising a supporting base plate; means defining a combustion chamber arranged above said plate and comprising a plurality of helically wound pipe coils disposed one above the other and about an upright axis; a steam and water drum above said coils; water circulating conduits communicatively connecting said coils and said drum; a plurality of upright supporting posts arranged about said coils and supported at their lower ends by said plate and supporting said drum by their upper ends; and means securing said coils to the sides of said posts so that the posts also support the coils from said plate and maintain the coils in their proper relative position with respect to one another.

BERNARD GOERG.
